SETTING GAUGE

Filed Nov. 17, 1926

UNITED STATES PATENT OFFICE

GERARD A. DE VLIEG, OF ROCKFORD, ILLINOIS

SETTING GAUGE

Application filed November 17, 1926. Serial No. 148,971.

The present invention relates to improvements in setting gauges for positioning work blanks relative to an operating element.

The objects of the invention are to provide a new and improved setting gauge which is simple and sturdy in construction, which is accurate and precise in use, which comprises means for preventing lost motion, which comprises a setting point adapted to be moved quickly and conveniently into and out of operative position, and which can be accurately adjusted to adjust the position of the setting point.

Further objects and advantages will be come apparent as the description proceeds.

In the accompanying drawings:

Figure 1 is a fragmentary view partially in section of a grinding machine to which a setting gauge embodying the features of my invention has been applied.

Fig. 2 is a fragmentary sectional view of the setting gauge taken along line 2-2 of Fig. 3.

Fig. 3 is a fragmentary view partially sectioned along line 3-3 of Fig. 2.

Fig. 4 is a view showing the setting gauge in front elevation.

While the invention is susceptible of various modifications and alternative constructions, I have shown herein and will describe in detail the preferred embodiment, but it is to be understood that I do not thereby intend to limit the invention to the specific form disclosed, but intend to cover all modifications and alternative constructions falling within the spirit and scope of the invention, as expressed in the appended claims.

In the accompanying drawings, I have shown the preferred form of my invention applied to a grinding machine for sharpening reamers with inclined blades, but it is to be understood that the invention is applicable to a large variety of machine tools.

Referring more specifically to the drawings, the grinding machine comprises generally a frame 5 having a vertical standard 6 on the rear. A grinding wheel 7, which preferably is cup shaped and is inclined slightly from the perpendicular to the front

of the machine, is rotatably mounted in the vertical standard 6.

Mounted for reciprocation on the front of the machine, and across the face of the grinding wheel is a carriage 8 on which are adjustably supported a headstock 9 and a tailstock 10. An arbor 11 for supporting the cutter 12 is adjustably mounted between the centers of the headstock 9 and tailstock 10, and when the cutter has inclined blades, is adapted to be rotated through the headstock in timed relation to the reciprocation of the carriage 8 so as to compensate for the inclination of the blades of the cutter.

In sharpening cutters having a plurality of spaced blades, whether the cutter be indexed manually, or be indexed automatically, as described in my Patent No. 1,710,533, dated April 23, 1929, it is extremely important and is in fact necessary that the cutter be accurately positioned relative to the grinding wheel so as to produce the correct size, clearance and contour. To correctly position the cutter, whether it be initially, or after indexing, or during its reciprocatory movement, a setting gauge is provided which is fixed with reference to the position of the grinding wheel, and which is adapted to define the angular position of any blade of the cutter relative to the grinding wheel.

The setting gauge selected for illustration comprises a finger 13 having an offset portion 14 formed with a point 15. The upper end of the finger 13 is pivotally mounted on a pin 16 in a slot 17 in the lower end of a supporting bar 18. The lower end of the bar 18 with the downwardly and laterally opening slot 17 constitutes a slotted head for the finger 13. The finger point 15, when in operative position (shown in full outline in Fig. 2), is adapted to be engaged by the face of a cutter blade to position the cutter 12 relative to the grinding wheel. A finger grip 19 is formed on one side of the finger, and provides means whereby the finger can be swung upwardly into inoperative position (shown in dotted outline), or downwardly into operative position. To yieldingly retain the finger 13 in any one of its different positions, the pivoted end of the finger is

formed with a plurality of notches 20 and 21, which are adapted to be selectively engaged by a spring pressed detent 23 slidably mounted in a bore 24 in the lower end of the 5 supporting bar 18. The detent is pressed downwardly by a coil spring 25, which is disposed in a bore 26 in the inner end of the detent, and which impinges against the inner end of the bore 24.

10 The supporting bar 18 is non-rotatably and adjustably disposed in a vertical bore 27 formed through a sleeve 28 on a bracket 29. The latter preferably is formed integral with the hood 30 for the grinding wheel 7. To 15 prevent rotation of the bar 18, a suitable bolt 28^a is threaded through the sleeve 28 into a longitudinal spline groove 18^a in the bar. The upper end of the bore 27 is closed by a threaded bushing 31. Formed on the 20 upper end of the bar 18 is a threaded shank or stem 32, which extends upwardly through the bushing 31, and which is adapted to be adjusted longitudinally by a nut 33 to be clamped in adjusted position by a nut 34. 25 A micrometer ring 35 on the sleeve 28 encircles the adjusting nut 33, and serves to indicate the position of adjustment of the bar 18 and hence the finger 13. To take up lost motion, a coil spring 36 is positioned on the stem 32, and butts at one end against the upper end of the bar 18 and at the other end against the inside of the bushing 31.

In using the setting gauge, the finger 13 is moved into operative position to define the 30 desired position for each blade of the cutter as it is presented to the grinding wheel. With the finger 13 in operative position, the cutter 12 is angularly adjusted to bring one of its blades into contact with the point 15. If 35 the finger is to be used only for initially adjusting the cutter, it is then moved upwardly into inoperative position.

It will be evident that I have provided a 40 setting gauge which is convenient and accurate, which can be adjusted into any desired position, which can be moved out of the way when not in use, and which is simple and sturdy in construction.

I claim as my invention:

50 1. A setting gauge having, in combination, an upright sleeve, an upright bar non-rotatable in said sleeve, said bar being formed in its lower end with an axial opening and with a slotted head, and being formed on its upper 55 end with a threaded stem, a bushing closing the upper end of said sleeve and fitting about said stem, an adjusting nut mounted on said sleeve and engaging said stem, a lock nut on said stem, a coil spring in said sleeve abutting 60 at its opposite ends against the upper end of said bar and against the inside of said bushing, a setting finger pivotally mounted at one end in said slotted head, the pivoted end of said finger being formed with 65 a plurality of notches, and a spring pressed

detent mounted in said bar and adapted to selectively engage said notches to hold said finger in any one of a plurality of positions.

2. A setting gauge having, in combination, 70 a support, a member adjustably mounted in said support, and having a slotted head on one end, a setting finger pivotally mounted at one end in said slot, said finger having a setting point and a finger grip, and spring pressed means for holding said finger selectively in operative position or in inoperative 75 position.

3. A setting gauge having, in combination, 80 a support, an elongated member longitudinally adjustable in said support, a setting finger pivotally mounted at one end in one end of said member, said finger having a setting point, and spring pressed means for holding said finger selectively in operative position or in inoperative position.

4. A setting gauge having, in combination, 85 a support, a bar non-rotatably mounted in said support, means for adjusting said bar longitudinally in said support, spring means pressing said bar in one direction to take up lost motion, a setting finger pivotally mounted in one end of the bar for movement into any one of a plurality of positions, and spring actuated detent means for holding said finger yieldingly in position.

5. A setting gauge having, in combination, 90 a vertical sleeve, an upright bar non-rotatable in said sleeve, said bar being formed in its lower end with an axial opening, and on its upper end with a threaded stem, means for adjusting said stem vertically, a setting finger pivotally mounted at one end in the lower end of said bar, the pivoted end of said finger being formed with a plurality of notches, and a spring pressed detent mounted in said axial 95 opening and adapted to selectively engage said notches to hold said finger in any one of a plurality of positions.

6. A setting gauge having, in combination, 100 a support, a member adjustably mounted in said support, a setting finger adjustably mounted in said member, said finger having a setting point, and spring actuated means for yieldingly holding the said finger selectively in different predetermined positions of 105 adjustment.

In testimony whereof, I have hereunto affixed my signature.

GERARD A. DE VLIEG.
